UNITED STATES PATENT OFFICE

2,502,169

PORTABLE ELECTRIC LANTERN

Charles S. Packer, Chicago, and Marvin R. Olsen,
Glen Ellyn, Ill., assignors to Justrite Manufacturing Company, Chicago, Ill., a corporation of Illinois

Application January 11, 1947, Serial No. 721,614

3 Claims. (Cl. 240—10.63)

1

The invention relates to electric lanterns of the type generally used for signalling and other temporary illuminating purposes and has reference more particularly to an improved lantern of this character having a plurality of lamps supported by a switch member and which is mounted for reciprocating movement with respect to the reflector so that one of said lamps may be positioned centrally of the reflector at the same time that the circuit through the lamp is closed.

An object of the present invention resides in the provision of an improved switch member with actuating means therefor and which will have a plurality of indexed positions upon manual manipulation to establish an electrical circuit including one of said lamps depending on the particular indexed position of the switch member.

A further object is to provide a switch member for use in lanterns of the character described which will have a plurality of projections adapted to engage depressions formed in guiding means therefor so that the switch member is indexed in a plurality of positions.

Another object of the invention is to provide switch mechanism for electric lanterns and the like including a switch member mounting a plurality of lamps in combination with guiding means for guiding the member in its reciprocating movement and wherein said guiding means constitutes one of the electric terminals for the switch and also coacts with the switch member in a manner to index the same in certain on and off positions.

A further object resides in the provision of an electric lantern having resilient guiding rails for a reciprocable switch member and wherein the guiding rails are provided with depressions to function as detent means with respect to the switch member for positioning and maintaining the member in indexed positions, certain of which constitute on and off positions of the switch.

With these and other objects in view the invention may consist of certain novel features of construction and operation as will be more fully described and particularly pointed out in the specification, drawings and claims appended hereto.

In the drawings, which illustrate an embodiment of the invention and wherein like reference characters are used to designate like parts—

Figure 1 is a view in cross section of a portable electric lantern equipped with the improved switch structure of the invention;

2

Figure 2 is another view in cross section through the lantern as shown in Figure 1;

Figure 3 is a view in end elevation showing the reflector of the present lantern in combination with the reciprocable switch member;

Figure 4 is a perspective view of the switch member forming the reciprocable mounting for the lamps;

Figure 5 is a transverse sectional view taken substantially along line 5—5 of Figure 2 and looking in the direction of the arrows; and

Figure 6 is a transverse sectional view taken substantially along line 6—6 of Figure 2 and looking in the direction of the arrows.

15 The electric lantern selected for illustrating the present invention is similar in many respects to the lantern described and claimed in the patent to Packer No. 2,289,276, granted July 7, 1942, and entitled Portable electric lantern. Such

20 lanterns are generally used for signalling by railroad men although, of course, they may be used for other purposes where temporary illumination is required. As best shown in Figures 1 and 2, the housing 10 has a detachable cover or cap 11 at one end and a reflector head 12 at its other end. The housing 10 is formed of two substantially U-shaped parts 14 and 15, Figure 6, connected together in overlapping relation by means of the rivets 16 which likewise secure a

25 finishing channel strip 17 to the housing at the overlapping edges of parts 14 and 15. The housing 10 is closed at one end by said reflector head 12 which comprises a substantially circular plate 18 having an annular flange 20 which telescopically receives the reflector 21 and secures the

30 same in proper position as by means of a plurality of screws 22. The reflector head 12 is secured in operative position at this end of the housing 10 by means of brackets 23 and 24. Each of said brackets has one leg thereof secured to the plate member 18 as by the screws 25 and the other leg of the bracket is received in one of the opposed recesses 26 provided therefor in the

35 housing 10. The brackets are secured to the housing by means of a plurality of rivets 27 which extend through plates 28 located exteriorly of housing 10 and which plates may have tubular end portions for receiving wire supporting elements, as clearly shown in detail in Patent No.

40 2,289,276, previously referred to.

45 The other end of housing 10 is normally closed by a detachable cover or cap 11, as previously described, and which is provided with a leaf spring 30 secured thereto by rivets such as 31,

50 55 the said leaf spring being adapted to resiliently

engage one end of a battery set 32 for resiliently holding the battery set within the housing and to prevent displacement thereof. The cover 11 is detachably connected to the housing by means of oppositely disposed buttons 33 projecting through aligned openings in the housing and the marginal flange of the cover. The buttons 33 are secured adjacent one end to the flat springs 34 disposed adjacent the inner face of the housing and which springs are connected to said housing by means of rivets 35.

The plate 18 of the reflector head is formed with an elongated slot 36, Figure 5, through which projects a spring contact element 37 secured by means of rivet 38 to an insulating plate 40. The rivet 38 likewise secures a center contact plate 41, Figure 6, to the said insulating plate 40, which contact plate is of metal and is adapted to be engaged by the spring terminal 42 of the battery set 32. The plate 41 is disposed in concentric relation with respect to an opening 43 formed in the square plate 44. The said plate 44 is suitably secured to the insulating plate 40 and to plate 18 by means of the rivets 45 which extend through the said plates to depend below plate 18 and to additionally secure to said plate in depending relation therewith the resilient guiding members 46 and 47. It will be seen that the members have spaced relation on the respective sides of the spring contact element 37 and that said resilient guiding members extend in a direction parallel to the longitudinal axis of slot 36. As a result of the structure described the said guiding members 46 and 47, plate 18, and the square plate 44 are in electrical contact with each other so that these elements comprise the negative terminal of the electric circuit to the lamps since plate 44 is in electrical contact with the leaf spring terminal 48 of the battery set 32.

The reflector is formed with a concave or dished surface centrally of which there is provided an elongated slot 50, Figure 3, to provide a channel by reason of the angular disposition of the marginal walls 51 bordering the said slot 50. The channel provides a seat for and the channel receives a movable switch member 52, Figure 4, which consists of side walls 53 and 54 connected by a connecting wall or web 55. The switch member is mounted within the channel provided by the angularly disposed walls 51 of the reflector 21 and the member is yieldingly maintained in position within said channel by the resilient guide rails 46 and 47 which in addition to functioning as guiding means are provided with a plurality of spaced depressions 56 for indexing purposes. In this connection, it will be observed that the switch member 52 is formed with a plurality of projections 57 provided along the edges of the side walls 53 and 54. The projections are spaced a distance approximately equally the spacing of depressions 56 so that when the parts are in contacting relation, as shown in Figure 2, the guiding rails 46 and 47 will function as detent means with respect to the switch member to releasably maintain the switch member in desired indexed position, which may constitute an on or an off position of said switch member.

The switch member 52 provides a mounting for a plurality of lamps such as 60 and 61, each of which is mounted within a socket 62 which extends through a suitable aperture in the connecting web 55 of the switch member. The extending portions of socket 62 have threaded secured thereto a nut 63 which holds the socket to the switch member, the nuts 63 having a center sleeve

of insulating material through which extends the center contacts for the lamps, respectively. The center contact for lamp 60 is designated by numeral 64, whereas, the center contact for lamp 61 is designated by numeral 65. The nuts 63 of the respective lamps 60 and 61 are connected by insulating plate 66. It will therefore be apparent that the switch structure of the invention is adapted to complete a circuit from the battery set through either one of the lamps 60, 61, depending on the position of switch member 52 with respect to the reflector head and reflector of the lantern. The reciprocable mounting for member 52, which makes possible the establishment of an electric circuit through either one of the lamps selectively, is releasably held in desired indexed position by the detent means including the projections 57 on the switch member and depressions 56 on the guiding rails. Said guiding rails therefore perform a dual function since they resiliently engage the side walls 53 and 54 of the switch member for indexing purposes and also have contacting relation with the switch member to provide one terminal of the electric circuit to the lamps, namely, from the leaf spring terminal 48 of the battery set through plate 44, rivets 45 to said guide rails 46 and 47 and thus to the switch member 52 and through lamps 60 and 61, the other terminal comprising the center contacts 64 and 65, spring contacting element 37, the center rivet 38 and the spring terminal 42.

For reciprocating the switch member 52, a pivot stud 68 is provided by the reflector head 12, the said stud being suitably secured to plate 18 in depending relation as shown in Figure 2. The annular flange 20 and the reflector 21 are each provided with a slot or recess designated 69, Figure 5, located adjacent the stud 68 and which slot or recess is provided for receiving the actuating lever 70 having an exteriorly projecting handle portion 71 and a part 72 located within the reflector head portion in the vicinity of slot 36. The actuating lever 70 is pivotally supported by the pivot stud 68 and when the parts are operatively assembled it will be observed that part 72 is adapted to enter recess 73, Figure 4, formed in wall 53 of the switch member 52 and which recess is provided with abutments on the respective sides thereof, whereby part 72 is properly confined within said recess and operative upon pivotal movement of lever 70 for effecting reciprocating movement of the switch member 52. Accordingly, upon manipulation of the actuating member 70 movement may be imparted to switch member 52 to position the same as shown in Figure 3, in which position of the member the electric circuit to lamp 61 is closed. When the switch member is centrally positioned as shown in Figure 1 the electrical circuit to both lamps is open and thus neither lamp is lit. It is also possible to locate the switch member in a position opposite to that shown in Figure 3 whereby lamp 60 will be centrally positioned and the circuit to the same will be automatically closed since the contact element 37 will be in contacting relation with the center contact 64. The switch member is yieldingly held in each of the positions as above described by the detent means including the projections 57 on the member which have coacting relation with the recess 56 formed in the guiding rails 46 and 47.

The invention is not to be limited to or by details of construction of the particular embodiment thereof illustrated in the drawings, as various forms of the device will of course be apparent

to those skilled in the art without departing from the spirit of the invention or the scope of the claims.

What is claimed is:

1. In an electric lantern, a housing having a slot adjacent one end thereof, a source of electrical energy, means associated with said housing for establishing an electrical circuit with said source of electrical energy including electrical contact means, a movable switch member having electrical contact means adapted to engage said first named electrical contact means, a plurality of lamps supported by said switch member and extending through said slot whereby said lamps are disposed exteriorly of the housing, an actuating device mounted upon and operable exteriorly of the housing and articulatedly associated with said switch member for moving the member in a direction longitudinally of said slot to locate the member in desired operative position, and guiding means for the switch member comprising spaced resilient rails included in said electrical circuit, said spaced resilient rails having indexing means and being yieldingly biased into yielding contact with the switch member for releasably maintaining the switch member in desired operative position.

2. In an electric lantern, the combination of a housing including a reflector provided with a channel, an opposed wall, a source of electrical energy, contact means in electrical association with said electrical energy, a movable switch member mounted in said channel and having contact means engageable with said first named contact means to complete and interrupt an electrical circuit established through said switch from said source of energy, guiding means fixed to said opposed wall including spaced resilient rails having yielding contact with said switch member, a pivoted actuating member extending exteriorly of the housing for manual operation, said actuating member having a part articulatedly associated with the switch member for operating said member, said resilient rails having spaced depressions

formed therein and said switch member having projections coacting with said depressions to provide detent means for positioning and releasably maintaining the movable switch member in desired position.

3. In an electric lantern, the combination of a housing having a transversely disposed wall of concave formation adjacent one end thereof provided with a slot substantially centrally of the wall and having a channel-shaped recess formed by the angular disposition of the walls on each longitudinal side of the slot, a source of electrical energy, means for establishing an electrical circuit with said source of electrical energy including a movable switch member mounted in the recess, said switch member including spaced walls having slidable association with the walls of said recess respectively, guiding means for the switch member including spaced resilient rails each having yielding contact with a wall of said switch member, a lamp mounted in said switch member and extending through said slot and being disposed exteriorly of said wall of concave formation, said resilient rails each being fixed to the housing and having depressions in spaced relation longitudinally thereof, and said walls of the switch member each having projections adapted to coact with the said depressions when the parts are in contacting relation for releasably holding the switch member in any one of a plurality of positions.
